(57) **CLAIM**

The ornamental design for a connector, as shown and described.

DESCRIPTION

FIG. 1 is an enlarged top, left perspective view of a left side end part of a connector showing my new design;
FIG. 2 is an enlarged top, right perspective view of a right side end part of the connector;
FIG. 3 is a front elevational view of the connector;
FIG. 4 is a rear elevational view thereof;
FIG. 5 is a top plan view thereof, a bottom plan view thereof being a mirror image;
FIG. 6 is a left side elevational view thereof;
FIG. 7 is a right side elevational view thereof;
FIG. 8 is a reduced top plan view thereof;
FIG. 9 is an enlarged right side elevational view thereof;
FIG. 10 is a right side elevational view thereof along the line 10—10 of FIG. 3; and,
FIG. 11 is a left side elevational view thereof along the line 11—11 of FIG. 3.
The cable is shown broken away in FIGS. 1—5 so that the ends could be shown enlarged in a single view.
